UNITED STATES PATENT OFFICE

NELSON WILLIAM ALLAN JACKSON, OWEN SOUND, ONTARIO, CANADA

PLIERS

Application filed January 16, 1929. Serial No. 332,932.

This invention relates to gripping tools, and has particular reference to an improvement in pliers.

The invention primarily comprehends a pliers which includes a pair of opposed members defining the handle and jaw portions and having a connection therebetween by virtue of which a binding action is set up when the jaws are disposed in gripping relation to an object, which binding action eliminates play and serves to maintain the gripped relation of the jaws with the object but without maintaining undue pressure on the handle portion.

15 The invention further contemplates an improved construction of pliers in which the members thereof are joined by interengaging means of connection formed integral with the members and which means specifically embodies the formation of an arcuate dovetail groove in one of the members and an arcuate dovetail rib on the opposite member formed on the confronting faces of the overlapped sections of the members at the juncture of the 20 handle and jaw portions thereof.

25 The invention further embodies means provided at an end of the grooved portion for limiting the opening of the jaws, which means also serves to prevent the complete separation 30 or disassembly of the members.

Other objects of the invention reside in the simplicity of construction of the pliers, the economy with which they may be produced and the general efficiency derived therefrom.

35 With the above recited and other objects in view, reference is had to the following description and accompanying drawings, in which there is exhibited one example or embodiment of the invention, while the claims 40 define the actual scope of the same.

In the drawings:

Figure 1 is a plan view of the pliers in closed condition.

45 Figure 2 is an edge view thereof.

Figures 3 and 4 are fragmentary plan views of the inner faces of the members.

50 Figure 5 is an enlarged fragmentary longitudinal sectional view taken approximately on the line indicated at 5-5 in Figure 1.

Figure 6 is a fragmentary plan view of the pliers in opened condition.

Referring to the drawings by characters of reference, the pliers include a pair of members 10 and 11 which define the jaws 12 and 13, the handles 14 and 15 and the intermediate overlapping portions 16 and 17. In lieu of providing a pivotal connection in the form of a rivet, the inner confronting faces of the jaws 16 and 17 are respectively formed with an arcuate rib 18 and an arcuate groove 19 which are of dovetail configuration in cross section, the groove 19 being slightly wider at the end 20 than at the end 21 and being of gradually decreasing width from the end 20 to said end 21. The arc of the rib 18 and groove 19 are struck from a common center disposed between the jaw portion of the members and the rib and groove. After the members 10 and 11 are assembled by engaging the rib 18 in the groove 19, means such as an out-struck lug 22 is provided at the end 21 of the groove to limit the opening of the jaws and to function to prevent complete separation or disassembly of the members.

In use and operation, closing of the jaws 12 and 13 upon an object to be gripped sets up a frictional binding action of the rib 18 in the groove 19 which operates to hold the jaws in gripped relation to the article. Due to this construction also, it has been found that a materially reduced pressure on the handles is necessary to the tightening of the jaws while play between the jaws is absolutely eliminated while the same are in gripped relation to an object. It is also apparent that by providing the connection as an integral part of the members, the usual rivet is eliminated, thereby making for a cheaper construction and a reduction in the cost of assembly.

What is claimed is:

1. Pliers including a pair of opposed members each comprising a handle and a jaw portion, one of the members having an arcuate groove, the sides of the groove having their centers substantially at the inner portion of the jaw of the member, and an arcuate rib on the other member with the sides of the rib having their centers substantially at the in-

ner portion of the jaw of the said other member.

2. Pliers including a pair of opposed members each comprising a handle portion and a jaw portion and interengaging means of connection therebetween formed integral with said members, said means of connection consisting of an arcuate dovetail grooved portion of one of said members and an arcuate dovetail rib portion of the other of said members, said grooved and rib portions being struck from a common center disposed at a point on the jaw side of the connection.

3. Pliers including a pair of opposed members each comprising a handle portion and a jaw portion, one of said members having an arcuate groove and the other member having an arcuate rib engaging with the groove and constituting the sole means of connection therebetween, the arc of the groove and rib struck from a common center disposed between the jaw portions of the member and said rib and groove.
